UNITED STATES PATENT OFFICE.

JOSEPH W. OSTEN, OF CHICAGO, ILLINOIS, ASSIGNOR, BY MESNE ASSIGNMENTS, TO AUTO FABRICS PRODUCTS, INC., A CORPORATION OF ILLINOIS.

AUTOMOBILE WINTER TOP.

Application filed May 4, 1925. Serial No. 27,652.

This invention relates to automobile tops in general and more particularly to such tops as are adapted to be converted for winter use. It is obviously very advantageous to 5 convert an ordinary touring car with the usual top therefor into a closed car during cold and inclement weather. It is usually the case with touring tops for automobiles that they are constructed with a more or less 10 rectangular shape and the lines of the body of the car merge inwardly toward the front, such that the portion of the top at either side of the car extends outwardly of the vertical plane of the side of the body. It is thus 15 very difficult to provide a means for neatly and efficiently fitting the winter top panels of a car to the ordinary touring top to convert the latter into a winter top. Heretofore this has been done by providing a block 20 of wood on either side of the car for filling in the space between the top edges of the side panels and the depending edges of the top. This obviously required a large amount 25 of work for accommodating slight variations in sizes of body or top. In addition this method required a large amount of work, such as drilling of holes, etc.

It is accordingly an object of this invention to provide an improved means for 30 converting a touring car having an ordinary top into a closed car by providing said top with simplified improved side closures adapted to be readily secured in place, without necessitating any changes in the top structure.

35 It is an important object of this invention to provide an improved side panel supporting means adapted to be readily disposed between the top edges of winter side panels and the sides of the ordinary automobile top, 40 said panel supporting means being simple, economical, easily installed and readily adjustable to accommodate variations in structure of tops and bodies.

Other and further important objects of 45 this invention will be apparent from the disclosures in the specification and the accompanying drawings.

50 This invention (in a preferred form) is illustrated in the drawings and hereinafter more fully described.

On the drawings:

Figure 1 represents a side elevation of a winter top embodying the principles of this invention.

Figure 2 is a longitudinal vertical section 55 of the same with parts removed.

Figure 3 is a fragmentary detail horizontal section taken on line III—III of Figure 2.

Figure 4 is a detail fragmentary horizontal section taken on line IV—IV of Figure 1.

Figure 5 is a fragmentary detail section taken on line V—V of Figure 3.

Figure 6 is an enlarged fragmentary detail section taken on line VI—VI of Figure 4.

Figure 7 is a fragmentary vertical detail section taken on line VII—VII of Figure 3.

Figure 8 is a fragmentary detail view taken on line VIII—VIII of Figure 1.

Figure 9 is an enlarged detail section 70 taken on line IX—IX of Figure 2.

Figure 10 is a fragmentary detail section taken on line X—X of Figure 2.

Figure 11 is a detail sectional view taken 75 on line XI—XI of Figure 2.

Figure 12 is a detail sectional view taken on line XII—XII of Figure 1.

Figure 13 is a detail plan view of the longitudinal extending strip illustrating the method of attachment to the front end of 80 the automobile top.

Figure 14 is a section taken along line XIV—XIV of Figure 13.

Figure 15 is a vertical section, with parts removed, of a modified form of a device embodying this invention.

Figure 16 is an enlarged detail section taken on line XVI—XVI of Figure 15.

Figure 17 is a detail side view of the device shown in Figure 16.

Figure 18 is a detail plan view of a modified form of the parts shown in Figure 13.

Figure 19 is a detail plan view of a modified form of the parts shown in Figure 18.

As shown on the drawings:

Referring to Figure 1, there is shown a usual touring top 1 mounted in a standard position on an automobile body 2. Mounted on the forward end of the body 2 is a wind shield 3 of the usual type which has provided thereon at the top thereof a transversely extending rod 4. Secured to the rod 4 on either side thereof are the usual brackets 5 and clamps 6 pivotally mounted on said brackets for holding the top 1 in its stretched raised position. Engaged around each clamp 6 (Figure 13) is a small flange clamp member 7. The clamp 7 is rigidly secured

by bolts or other suitable means to a longitudinally extending bar 8. Each longitudinally extending bar 8 is supported intermediate its ends by means of a clamp member 9 mounted on a standard member 10 of the top frame elements (see Figures 2 and 9). Rearwardly of each clamp 9 the end of the bar 8 is secured to an upright bar or rod 11, the upper end of which is hook shaped and engaged over another member or strut iron 12 of the top frame elements (see Figures 3 and 10). The bar 11, as shown in Figures 10 and 2, extends downwardly and is secured to the body 2. It will be noted by reference to Figure 3 that each bar 8 extends rearwardly substantially in the vertical plane of the side of the body to a point adjacent to the line in which said plane meets the vertical plane of the side of the 20 top.

As shown in detail in Figure 4, the rear end of a longitudinally extending outer bar 15 is secured to the upper portion of a top frame element 13 by a clamp 14 or other suitable means. Each bar 15 extends forwardly substantially in the vertical plane of the side of the top 1 and is secured at its forward end to a transverse bow or top frame element 16, as shown more particularly in Figure 7. The bar 15 has folded therearound a fabric material 17 similar to that of which the top covering is made. The material 17 is sewed to provide a sheath for said bar 15. As shown in Figure 7, the material 17 is slotted and provided with eyelets 18. Secured to the element 16 are rotatable flat headed turn pins 19 which are adapted to extend through the eyelets 18 and be turned to hold said material 17 and bar 15 therein secured to the element 16. The material 17 extends inwardly over the upper edge of the bar 8 and is looped therearound, as shown in Figure 6, and is sewed to provide a sheath for containing said bar 8. The material 17 extends rearwardly on the bars 15 and 8 and bridges the space between said bars.

Panel members 20 are secured to the bars 8 by means of bolts or rivets 21 and are secured at their lower margins to the body of the car by means of screws 22, or other suitable means. The panels 20 are provided with metal reinforcing or brace strips 23. Secured to the doors 24 of the car are door panels 25 which are provided with metallic inner frames having vertical metal strips 26, the lower ends of which are substantially Z-shaped and secured to the doors 24 as shown in Figure 11. There is provided at the forward inclined edge of each front door panel 25 a strip 27 which is adapted to be secured to the bar 8 and the body 2 as shown in Figure 1 for enclosing the space between each front door panel 25 and the wind shield 3. As shown in Figure 12 the vertical

edges between the panels 20 and the door panels 25 and 25^a are constructed to overlap so as to be as air proof as possible. As shown in Figure 6, the outer bars 15 are additionally supported intermediate their ends by means of hooks 28 secured to the outer sides of the material on the bars 15 or directly to the bars 15, if preferred. This arrangement tends to insure a more perfect weather proof connection between the top 1 and the bars 15 with the material 17 spanning the space between the bars 8 and 15. The hooks 28 are distributed along the lengths of the bars 15 and are adapted to engage in slots or openings in the hem or margin 29 of the top 1. There is provided on each side at the extreme rear of the top 1 inside of the top covering an inner flap 30 (Figure 8) which is secured to the upper edge of each rear panel 20.

There is shown in Figures 15, 16 and 17 a modified form of securing the rear end of the bar 8^a to the inclined top brace bar 31. In this case the intermediate clamps 9 and 11 are provided as in the previous embodiment, but the bars 8^a are longer than the bars 8 and extend much farther to the rear and are clamped to a rear top frame element 31 by means of clamps 32, each of which is provided with a bolt 33 secured thereon. The bolt 33 extends through a slot 34 in the bar 8^a and is clamped thereto by means of a nut and washer 35. In this modification the outer bars 15 would also extend rearwardly to a point adjacent the clamps 32 and the material 17 would likewise extend further to the rear than in the previous embodiment.

As shown in Figure 18, there is provided a modified means of connecting the bar 8 to the clamp 6 which consists in providing an integral flange 37 on the front end of each bar 8. The flange 37 is adapted to be spring pressed by means of a butterfly nut 38 engaging a spring 39 for pressing said flange against a shoulder on the clamp 6. As shown in Figure 19, the device of Figure 18 is further modified to provide an angle bracket 36 which may be longitudinally adjustable with respect to the bar 8 by providing the bar with a slot or with a plurality of spaced openings for receiving the retaining bolt 40.

It will be seen that I have provided a means for converting an ordinary touring car top into a winter top. It will be obvious that the bars 8 and 15, together with the connections therefor and the material 17 therebetween provide a very simple and efficient means disposed between the outer edges of the top and the top margins of the door and side panels 20, 25 and 25^a, whereby the winter sides may be easily and quickly installed on almost any touring car for converting the top into an efficient winter top.

I am aware that many changes may be

made, and numerous details of construction may be varied through a wide range without departing from the principles of this invention, and I therefore do not purpose 5 limiting the patent granted hereon, otherwise than necessitated by the prior art.

I claim as my invention:

1. In combination with automobile side panels, an automobile top, flexible means extending inwardly from adjacent the longitudinal edges of said top to said side panels, and means for fitting said flexible means to said side panels, of means for fitting said flexible means to said top comprising a 15 longitudinally extending hook carrying bar mounted along the edge of said top with its hooks engaged in the edge portion of the material forming the top.
2. The combination with a touring car top, 20 of a longitudinally extending outer bar, a longitudinally extending inner bar spaced therefrom, an adjustable support for the rear end of said inner bar, flexible means connecting said bars, hooks on said outer bar

adapted to be engaged in the margin of the 25 lining of said top, a plurality of side panels, means for connecting said side panels to said inner bar, and means for securing the lower portions of said side panels to the body of said car.

3. The combination with an automobile touring top and body, of a longitudinally extending outer bar secured to the inner margin of said top, a longitudinally extending inner bar spaced from said outer bar, means 35 for securing the front end of said inner bar to the automobile windshield frame, a hook member secured to said inner bar, said hook member detachably supporting a portion of said inner bar on a strut iron of said top and 40 securing said inner bar to the automobile body, flexible material connecting said outer bar with said inner bar, and side panels supported on said inner bar and connected to the automobile body.

In testimony whereof I have hereunto subscribed my name.

JOSEPH W. OSTEN.
